UNITED STATES PATENT OFFICE.

PALMER COX, OF NEW YORK, N. Y.

DESIGN FOR A HANDKERCHIEF.

SPECIFICATION forming part of Design No. 23,436, dated July 10, 1894.

Application filed February 19, 1894. Serial No. 500,797. Term of patent 14 years.

To all whom it may concern:

Be it known that I, PALMER COX, a citizen of the United States, and a resident of the city, county, and State of New York, have invented and produced a new and original Design for a Handkerchief or Similar Article, of which the following is a full, clear, and exact specification, reference being had to the drawing forming part thereof.

10 The object of my invention is to produce a design such as is not only new and original but also has a pleasing effect to the eye which is peculiar to itself, thus being attractive and popular.

15 My design as shown in the drawing is produced on woolen, silk, cotton and other fabrics.

The drawing represents a handkerchief or similar article on which is shown my design.

20 The leading feature of this design consists in the figures of Twin Brownies arm in arm which fall entirely within a square so set upon a second square as to allow only its corners to protrude beyond the sides of the first square. These squares have for a common center the center of the handkerchief.

25 These Twin Brownies are the center of attraction when viewed in connection with the other Brownie figures which are grouped around as follows: First:—On one border about on line with and to the right of the

30 man Brownie also looking at them with amusement. Thirdly:—On the border, beneath the Twin Brownies there appears the half figure of an ordinary Brownie within a circular outline. Fourthly:—On the border, above the Twin Brownies there appears the half figure 40 of an ordinary Brownie within a circular outline. Fifthly:—In the right hand lower and upper corners of the border of the handkerchief there also appears the half figure of an ordinary Brownie with smiling countenance, 45 within a circular outline. Sixthly:—In the left hand lower corner of the border of the handkerchief appears the half figure of a Turkish Brownie with smiling countenance, within a circular outline. Seventhly:—In the 50 left hand upper corner of the border of the handkerchief appears the half figure of a Spanish Brownie with smiling countenance, within a circular outline.

It is evident that if the leading feature of 55 my design is dispensed with there will still remain in the figures on the border viewed with respect to each other an independent feature of my design.

Some of the figures are drawn to represent 60 the characteristic dress of a peculiar country, thus serving to instruct the young, while the design affords pleasure and amusement to both young and old.

I claim—

1. The design for a handkerchief or similar article substantially as herein shown and described. 65
2. In the design for a handkerchief or similar article substantially as herein shown and described, the border. 70
